Primary Examiner — Richard Kearney(74) *Attorney, Agent, or Firm* — Dickinson Wright PLLC; Andrew D. Dorisio(57) **CLAIM**

The ornamental design for a mounting extrusion, as shown and described.

DESCRIPTION

1. Mounting extrusion

1.1 is a side view.

1.2 is a top view.

1.3 is another side view.

1.4 is a perspective view.

The broken lines shown in the drawings illustrate portions of the article and form no part of the claimed design.
